BRAKE

Filed Aug. 1, 1925

FIG. 2

FIG. 3

INVENTOR
GEORGE J. THOMAS
BY *John W. McConkey*
ATTORNEY

UNITED STATES PATENT OFFICE.

GEORGE J. THOMAS, OF SOUTH BEND, INDIANA, ASSIGNOR TO BENDIX BRAKE COMPANY, OF CHICAGO, ILLINOIS, A CORPORATION OF ILLINOIS.

BRAKE.

Application filed August 1, 1925. Serial No. 47,453.

This invention relates to brakes, and is illustrated as embodied in a front wheel brake for an automobile.

One feature of the invention relates to pivoting a pair of end shoes on a central shoe which is anchored at one end, thus providing a connected shoe assembly and simplifying the construction by using a single anchor for all three shoes.

Another feature of the invention contemplates the use of a novel and particularly strong anchor, suitable for trucks and the like, and which is especially easy of assembly. In one desirable arrangement, a stationary anchor part, shown as a radially-extending flange of the wheel spindle, extends adjacent the anchored shoe and is connected thereto by an anchor pin or other member which is confined in place in a novel manner by spaced parts of another shoe.

The above and other features of the invention, including various novel combinations of parts and desirable particular constructions, will be apparent from the following description of one illustrative embodiment shown in the accompanying drawings, in which:

Fig. 1 is a vertical section through the brake, just inside the front wheel, showing the shoes in side elevation;

Fig. 2 is a section on the line 2—2 of Fig. 1, showing the anchor; and

Fig. 3 is a section on the line 3—3 of Fig. 1, showing the connection of one of the end shoes to the central shoe.

In the illustrated brake, the shoes or their equivalents are arranged between a drum 10 and a backing plate 12 carried by the wheel spindle 14. Three shoes are shown, a central shoe 16, a reverse end shoe 18, and a servo end shoe 20. Each of the end shoes 18 and 20 is forked or otherwise formed at its end with spaced parallel arms 22 and 24 (Figs. 2 and 3) straddling the corresponding end of the central shoe 16. The shoes are forced against the drum by means such as a double cam 26, against the resistance of return springs 28 and 30.

Each of the end shoes 18 and 20 is connected to shoe 16 by a pivot pin 32 passing through aligned openings in shoe 16 and arms 22 and 24, and having a smooth head 34 slidably engaging the backing plate 12 to position the shoes laterally. Bushings 36

may, if desired, be pressed into the openings in shoe 16 and arms 22 and 24.

A part or flange 38, integral with or secured to knuckle 14, is preferably forked at its end to form arms 40 straddling the end of shoe 16, and in turn straddled by arms 22 and 24 of shoe 18. An anchor pin 42, passing through aligned openings in shoe 16 and arms 40, is confined in place by arms 22 and 24, which block its ends. A bushing 44 for the opening in shoe 16 may be provided if desired.

Since the anchor pin 42 and the pivot pins 32 are not fastened in any way, but merely slipped in place, the above-described arrangement provides a very simple assembly.

While one illustrative embodiment has been described in detail, it is not my intention to limit the scope of the invention to that particular embodiment, or otherwise than by the terms of the appended claims.

I claim:

1. A brake comprising, in combination, a central shoe anchored at one end, a pair of oppositely-extending end shoes connected to the central shoe adjacent its ends, and means for forcing the end shoes apart to apply the brake.

2. A brake comprising, in combination, a central shoe pivotally anchored at one end, a pair of oppositely-extending end shoes pivoted to the central shoe adjacent its ends, and means for forcing the end shoes apart to apply the brake.

3. A brake comprising, in combination, a central shoe anchored at one end, a servo shoe connected to the unanchored end of the central shoe and arranged to operate the central shoe, a third shoe connected to the central shoe at its anchored end, and means for forcing the servo shoe and the third shoe apart to apply the brake.

4. A brake comprising, in combination, a first shoe anchored at one end, another shoe forked to straddle the anchored end of the first shoe and having its forked end pivoted to the first shoe, and means for forcing the shoes outwardly to apply the brake.

5. A brake comprising, in combination, a first shoe and an adjacent stationary part, an anchor member connecting the shoe and said part, and a second shoe having spaced portions straddling the first shoe and said

- 2
- part and confining the anchor member in place.
6. A brake comprising, in combination, a first shoe and an adjacent stationary part, 5 an anchor member connecting the shoe and said part, a second shoe having spaced portions straddling the first shoe and said part and confining the anchor member in place, and a connection between the second shoe 10 and the first shoe.
7. A brake comprising, in combination, a first shoe and an adjacent stationary part, an anchor member connecting the shoe and said part, and a second shoe having a part 15 overlapping the first shoe and confining the anchor member in place.
8. A brake comprising, in combination, a stationary part forked at one end to form a pair of spaced arms, a brake shoe extending between said arms, an anchor member connecting the shoe and said arms, and means 20 separate from said shoe and disconnected from said member and arranged at the ends of said anchor member to confine it laterally.
9. A brake comprising, in combination, a stationary part forked at one end to form a pair of spaced arms, a brake shoe extending between said arms, an anchor member connecting the shoe and said arms, and a member 25 having spaced portions straddling the arms and shoe and confining the anchor member in place.
10. A brake comprising, in combination, a stationary part having a pair of arms, a 30 brake shoe having a part extending between said arms, an anchor member connecting the shoe and arms, and a second brake shoe having spaced portions confining the anchor member in place.
11. A brake comprising, in combination, a stationary part having a pair of arms, a 35 brake shoe having a part extending between said arms, an anchor member connecting the shoe and arms, a second brake shoe having spaced portions confining the anchor member in place, and means for anchoring the second shoe between the ends of the first shoe.
12. A brake comprising, in combination, a stationary part, a brake shoe, an axially floating anchor member connecting the part and shoe, and a second shoe having portions 40 confining the anchor member in place.
13. A brake comprising, in combination, a stationary part, a brake shoe, an axially floating anchor member connecting the part and shoe, and a second shoe anchored between the ends of the first shoe and having portions 45 confining the anchor member in place.
14. A brake comprising, in combination, a stationary pair of anchor arms, a brake 50 shoe extending between said arms, an anchor pin extending through aligned openings in the shoe and arms, and a second shoe having spaced parts blocking the ends of the anchor pin.
15. A brake comprising, in combination, 55 a stationary anchor part, a brake shoe extending adjacent said part, an anchor pin extending through aligned openings in the shoe and part, and a second shoe having spaced parts blocking the ends of the anchor pin.
16. A brake comprising, in combination, 60 a spindle having a radially-extending anchor arm, a brake shoe, an anchor pin passing through the arm and shoe, and a second shoe having spaced parts straddling said arm and the anchored part of the first shoe 65 and blocking the ends of the anchor pin.
17. A brake comprising, in combination, 65 a spindle having a radially-extending anchor arm, a brake shoe, an anchor pin passing through the arm and shoe, and a second shoe anchored between the ends of the first shoe and having spaced parts straddling said 70 arm and the anchored part of the first shoe 75 and blocking the ends of the anchor pin.
18. A three-shoe brake comprising, in combination, a central shoe, a pair of end shoes connected to opposite ends of the central shoe and having arms straddling the 80 ends of the central shoe, a stationary part having arms extending between the arms of one end shoe and straddling the end of the central shoe, and an anchor member 85 connecting the central shoe and the arms of the stationary part.
19. A three-shoe brake comprising, in combination, a central shoe, a pair of end shoes connected to opposite ends of the central shoe and having arms straddling the 90 ends of the central shoe, a stationary part having arms extending between the arms of one end shoe and straddling the end of the central shoe, and an anchor member 95 connecting the central shoe and the arms of the stationary part.
20. A three-shoe brake comprising, in combination, a central shoe, a pair of end shoes at opposite ends of and connected to the central shoe, a front-wheel spindle having a radially-extending flange, and an anchor for all three shoes connecting the 100 flange and one of the shoes.
21. A brake comprising, in combination, 105 a drum, a central shoe anchored at one end, and a pair of other shoes arranged at opposite ends of the central shoe and which are arranged to be effective at the same time 110 directly on the central shoe to force the central shoe about its anchored end against the drum.
22. A brake comprising, in combination, 115 a pair of shoes, one of which has spaced 120 portions.

arms straddling a part of the other, and an anchor part connected to at least one of the shoes and having spaced arms straddling said part of the other shoe and straddled by said spaced arms of the first shoe.

23. A connected sub-assembly of brake shoes including a central shoe constructed

and arranged to be anchored at one end, and at least two other shoes connected to the central shoe and arranged at opposite ends ¹⁰ thereof.

In testimony whereof I have hereunto signed my name.

GEORGE J. THOMAS.
